Patented Sept. 17, 1968

212,230

COMMUNICATION CONSOLE

George Bruce Kamp, Bala Cynwyd, Pa., assignor to International Telephone and Telegraph Corporation
Original design application June 23, 1966, Ser. No. 2,789. Divided and this application Nov. 14, 1967, Ser. No. 9,395

Term of patent 14 years

(Cl. D26—14)

FIG. 1

FIG. 2

FIG. 1 is a perspective view of a communication console showing my new design;

FIG. 2 is a rear elevation thereof.

This is a division of design application, Ser. No. D2,789, filed June 23, 1966.

I claim:

The ornamental design for a communication console, as shown and described.
